UNITED STATES PATENT OFFICE.

RAGNAR G. A. JOHANSON, OF CHICAGO, ILLINOIS.

DESIGN FOR A WHIPPING-TOP.

6,364.

Specification for Design.

Patented Oct. 5, 1920.

Application filed August 21, 1918. Serial No. 250,887. Term of patent 3½ years.

To all whom it may concern:

Be it known that I, RAGNAR G. A. JOHANSON, a citizen of Sweden, residing at Chicago, in the county of Cook and State of Illinois, have invented a new, original, and ornamental Design for Whipping-Tops, of which the following is a specification, reference being had to the accompanying drawing, forming part thereof.

Figure 1 is a plan view of a whipping top, showing my new design.

Fig. 2 is a view of a whipping top in elevation, showing my new design.

I claim:

The ornamental design for a whipping top, as shown.

RAGNAR G. A. JOHANSON.
